UNITED STATES PATENT OFFICE.

JACOB MÜLLER, OF BURBACH, GERMANY.

ADJUSTABLE WRENCH.

SPECIFICATION forming part of Letters Patent No. 451,833, dated May 5, 1891.

Application filed June 26, 1890. Serial No. 356,907. (No model.)

To all whom it may concern:

Be it known that I, JACOB MÜLLER, of Burbach, in the Kingdom of Prussia and German Empire, have invented a new and useful Adjustable Wrench, of which the following is a specification, reference being had therein to the accompanying drawings.

This invention relates to an adjustable wrench.

10 The improved spanner hereinafter described will operate upon nuts of any given diameter and is distinguished by its great simplicity. The same may be made of iron or wrought-steel.

15 In the accompanying drawings, Figure 1 is a sectional elevation, and Fig. 2 an edge view, of the wrench.

20 *a* is the handle or lever-arm, which is provided on both sides and at its upper end with serrations or teeth *d*. This handle carries the fixed jaws *c* of the spanner, while the other jaw *b* can be moved up and down thereon with a certain amount of play. The opening or cavity *f* of the jaw *b*, which slides 25 upon the handle *a*, is curved inwardly, so that the said jaw may be placed in a slightly-ob-

lique position, and be thereby enabled to rest with the edge *g* of its opening *f* against one of the teeth *d*, whereby the spanner may be arranged to fit in a very simple manner nuts 30 of any and every ordinary size. *h* is a peg or pin to prevent the falling off of the sliding jaw *b*.

What I claim, and desire to secure by Letters Patent of the United States, is—

35 The wrench composed of straight bar *a*, having similar teeth *d* on two opposite edges, the head rigid on the upper end thereof and projecting laterally in opposite directions to form two opposite rigid jaws *c*, the sliding member forming two jaws *b* and having transverse opening *f* through its center to receive bar *a*, said opening being contracted at opposite ends to form four biting-edges *g*, as shown, and for the purposes set forth. 40

45 In witness whereof I have hereunto set my hand in presence of two witnesses.

JACOB MÜLLER.
